UNITED STATES PATENT OFFICE.

KENNETH F. MACLELLAN, OF CHICAGO, ILLINOIS, ASSIGNOR TO CHICAGO CARTON COMPANY, OF CHICAGO, ILLINOIS, A CORPORATION.

CARTON.

Application filed September 16, 1921. Serial No. 501,017.

To all whom it may concern:

Be it known that I, KENNETH F. MACLELLAN, a citizen of the United States, residing at Chicago, in the county of Cook and State of Illinois, have invented certain new and useful Improvements in Cartons, of which the following is a specification.

My invention relates to cartons and has reference particularly to covers and carrying handles therefor.

The principal objects of my invention are to provide an improved carton cover; to construct the cover of two sections, one or both of which may be opened to afford access to the interior of the carton; to oppositely incline the sections so as to afford a peaked cover; to provide an improved handle for the carton; to mount the handle at the ridge of the peaked cover; to construct the handle so that it stands up above the cover; to afford a strong handle which is securely connected to the cover; to utilize a two-ply handle the two parts of which are connected respectively to the two sections of the cover; to form the handle integral with and intermediate of the cover sections; and in general to provide an improved carton which is inexpensive, easily constructed and of a more desirable form than cartons heretofore provided.

On the drawings,

Fig. 1 is a perspective view of a carton constructed in accordance with my invention.

Fig. 2, a transverse sectional view taken substantially midway between the ends of the carton, and

Fig. 3, a plain view of the blank form which the carton, carton cover and handle are formed.

The carton is illustrated as composed of a single blank, as this is the construction which I prefer, and the blank has sections 1 and 2, which, when the blank is folded, form the side walls of the carton, and sections 3 and 4 which form the end walls. These sections are bent at right angles to one another along the lines 5, 6 and 7 into rectangular form, and the section 1 has a flap 8 at the end which is bent at right angles thereto along the line 9 and cemented to the inner side of the section 4 along the edge, as indicated in Fig. 2. Each of the sections 1, 2, 3 and 4 has a flap indicated respectively at 10, 11, 12 and 13 along its lower edge each of which is

adapted to be bent at right angles to its respective section along the lines 14, 15, 16 and 17 respectively, so as to overlap in the usual manner and form the bottom of the carton, and the flap 11 has ears 18 which engage slots 19 of the flap 11 for holding the flaps in the folded position.

The end walls 3 and 4 of the carton are preferably formed with peaked upper extremities, as shown, forming gables with oppositely inclined edges 20 and 21, and a cover composed of sections 22 and 23, which assume an angular relation corresponding to the peaked upper ends of the wall sections 3 and 4, is hinged to the side wall 1 along the line 24 so as to close the top of the carton. The cover sections 22 and 23 are spaced apart in the blank and connected by correspondingly extending handle sections 25 and 26 which are united along their crown edges, and adapted to fold upon one another along the line 27 and have their ends connected with the respective cover sections and adapted to fold along the lines 28 and 29, forming a cover and two-ply handle as shown in Figs. 1 and 2. To insure proper interferfitting of the upper edges of the cover sections 22 and 23, the cut-out segment of the blank within the handle section 26 is not removed from the cover section 23 as in the case of the cover section 22, but is retained and bent at an angle to the cover section 22 to form a flap 30 which is overlapped by the upper edge of the cover section 22, and these cover sections are held edge to edge at their upper extremities by a seal or sticker 31 which is placed through the handle opening, and cemented to the cover sections.

The cover section 22 is preferably provided with end flaps 32 which fold along the lines 33 and are inserted at the inner side of the end walls 3 and 4 when the carton cover is closed, and each of these end walls has a flap 34 extending along the edge 21 and adapted to be bent inwardly to form a rest for the cover in the closed position. These flaps 32 and 34 serve to afford a more effective closure by covering the gaps that may occur between the cover sections and the end walls of the carton.

For holding the carton cover in the closed position, there is a flap 35 along the outer edge of the cover section 23 which folds along the line 36 and is adapted to be in-

serted at the inner side of the side wall 2 of the carton, this flap being retained in the inserted position by the lower edges of the end wall flaps 34 which engage the ends of 5 the cover section and its flap 35 substantially along the bend 36 and frictionally hold the flap against the carton wall 2.

With this carton construction, a substantial handle is afforded as it is composed of 10 two thicknesses of the carton material, and the handle is securely fastened to the cover as it is separately connected with each cover section. The blanks are easily and quickly 15 assembled and the cover, being composed of two hinged sections, permits the section 23 alone to be opened up, or the entire cover consisting of sections 22 and 23 may be opened.

While I have shown and described my invention in a preferred form, I am aware that 20 various changes and modifications may be made without departing from the principles of my invention, the scope of which should be determined by reference to the appended 25 claims.

I claim as my invention:

1. A folding carton comprising sides and ends connected together to form a tubular body, folding flaps forming a flat bottom, 30 and a top closure comprising two cover sections meeting edge to edge, corresponding handle sections integrally hinged to the meeting edges of said cover sections and tuck-in flaps on said cover sections for removably holding the same in place.

2. A folding carton comprising sides and ends connected together to form a tubular body, folding flaps forming a flat bottom, and a top closure integrally hinged to one 35

side only of the body and comprising two 40 cover sections meeting edge to edge, and corresponding handle sections on the meeting edges of said cover sections, said handle sections being integrally hinged to each other and to the cover sections. 45

3. A folding carton comprising sides and ends connected together to form a tubular body, foldable flaps forming a flat bottom, said ends having peaked upper edges, a peaked cover comprising two sections meeting edge to edge along a ridge, corresponding handle sections at the meeting edges of 50 said cover sections and integrally united therewith and tuck-in flaps on said cover sections for holding the same in place. 55

4. In a carton, the combination with a tubular body of a cover integrally hinged to one wall of the body and comprising a pair of sections and a two-ply handle at the juncture of the two sections, the layers of 60 which are integrally connected with each other and one such ply with each of the cover sections.

5. A carton having side and end walls connected to form a tubular body, a cover 65 hinged to one wall only of the body and comprising two sections and a two-ply handle, the plies of which are integrally connected to each other and one such ply to each of the cover sections, means permanently connecting said cover sections and holding the handle plies in engagement, said cover sections having tuck-in flaps removably holding the same in position and permitting the opening and closing of one 70 or both of said sections. 75

KENNETH F. MACLELLAN.
